UNITED STATES PATENT OFFICE

171,915

MARKET CHECK-OUT STAND

Kenneth L. Stapp, San Diego, Calif.

Application August 10, 1953, Serial No. 26,366

Term of patent 14 years

(Cl. D80—2)

To all whom it may concern:

Be it known that I, Kenneth L. Stapp, a citizen of the United States of America, residing in the city of San Diego, in the county of San Diego, State of California, have invented a new, original, and ornamental Design for Market Check-Out Stand, of which the following is a specification, reference being had to the accompanying drawing, forming a part thereof.

Figure 1 is a perspective view of a market check-out stand taken from the customer's aisle, showing the exit end of the stand and of the tunnel for carts, and showing my new design;

Figure 2 is a perspective view of the same taken from the cashier's side and showing a portion of the entrance end of the stand;

Figure 3 is an end elevational view of the exit end of the stand, with the tunnel for carts shown on the left;

Figure 4 is a fragmentary perspective view of the cashier's area of the stand, looking toward the customer's aisle and the entrance end of the stand; and

Figure 5 is a top plan view of the stand, with the entrance end at the left and the exit end at the right.

I claim:

The ornamental design for a market check-out stand, substantially as shown.
